[57] CLAIM

The ornamental design for a frying pan, as shown and
described.

DESCRIPTION

FIG. 1 is a top perspective view of a frying pan, showing
our new design;

FIG. 2 is a side elevational view thereof;

FIG. 3 is a view similar to FIG. 2 but from the opposite
side;

FIG. 4 is a top plan view thereof;

FIG. 5 is a bottom plan view thereof;

FIG. 6 is an end elevational view thereof from the left
of FIG. 2; and

FIG. 7 is an end elevational view thereof from the right
of FIG. 2.

FIG. 4

FIG. 5

FIG. 6

FIG. 7
